(57) **CLAIM**

The ornamental design for a television receiver, as shown and described.

DESCRIPTION

FIG. 1 is a front perspective view of a television receiver showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is an enlarged view of the delineated portion 9 in FIG. 1;

FIG. 10 is a front perspective view of a television receiver showing our new design in an alternate position;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a rear perspective view thereof;

FIG. 18 is an enlarged view of the delineated portion 18 in FIG. 10;

FIG. 19 is a front perspective view of a television receiver showing our new design in an alternate position;

FIG. 20 is a front elevation view thereof;

FIG. 21 is a rear elevation view thereof;

FIG. 22 is a left side elevation view thereof;

(Continued)

FIG. 23 is a right side elevation view thereof;
 FIG. 24 is a top plan view thereof;
 FIG. 25 is a bottom plan view thereof;
 FIG. 26 is a rear perspective view thereof;
 FIG. 27 is an enlarged view of the delineated portion 27 in FIG. 19; and,
 FIG. 28 is an enlarged view of the delineated portion 28 in FIG. 19.

The evenly dashed broken lines in the drawings illustrate portions of the television receiver that form no part of the claimed design. The dot-dot-dash broken lines in the drawings delineate portions of the design that are illustrated in enlargements and form no part of the claimed design.

1 Claim, 28 Drawing Sheets
